OIL COOLER

James E. Sullivan, Dayton, Ohio, assignor to
 United Aircraft Products, Inc., Dayton, Ohio,
 a corporation of Ohio

Application April 3, 1943, Serial No. 481,702

3 Claims. (Cl. 257—2)

1

This invention relates to heat exchange units, especially for use in cooling hot, viscous liquids such, for example, as the lubricating oil of internal combustion engines, and has particular reference to improvements in heat exchange units of the type comprising, generally speaking, a heat exchange portion in the form of a core which is surrounded by a passageway through which the liquid to be cooled flows prior to entering the core and through which the liquid may flow in by-passing relationship to the core in the event that the core may become obstructed to flow of the liquid therethrough due to congealation of the liquid contained therein or to any other cause.

One well known form of heat exchange unit of the type referred to and with which the present invention is concerned, comprises a casing enclosing the heat exchange core portion of the unit, and a jacket surrounding said casing and providing a passageway extending therearound. The jacket is provided at a suitable point, at the top thereof for example, with an opening for the inlet to said passageway of the liquid to be cooled, and the casing is provided at a point diametrically opposite or substantially diametrically opposite said inlet opening, at the bottom thereof for example, with an inlet opening for flow of the liquid from said passageway into the said heat exchange core portion of the unit. In addition, the casing is provided at a point diametrically opposite or substantially diametrically opposite said last mentioned opening, at the top thereof for example, with an opening for the outlet of the liquid from said heat exchange core portion, and the jacket is provided at a suitable point, at the top thereof for example, with an opening for the outlet of the liquid from said passageway. Normally, however, the jacket outlet opening is closed by a valve so that the liquid is prevented from by-passing the core portion of the unit and is required to flow therethrough. Said valve is, however, maintained normally closed by suitable yieldable means so that it may open under an abnormal pressure in the system of which the heat exchange unit is a part. Accordingly, if the core portion of the unit should become obstructed to flow of the liquid therethrough due to congealation of the liquid therein, or to any other cause, the pressure in the system will rise until said yieldably closed valve is forced open, whereupon the liquid will flow in by-passing relationship to said core portion until the congealed liquid therein has become decongealed or until such other cause of obstruction

2

to flow through said core portion as may exist has been removed. The valve then will close and flow of the liquid through the core portion will be resumed. The core portion of the unit thus is protected against damage by high pressures in the system such as might arise in the case of an internal combustion engine lubricating system due to starting of the engine following a period of idleness thereof during which the lubricant in the core portion of the unit may have become congealed, or due to surges of the lubricant resulting from sudden accelerations of the engine.

When the portion of the lubricant or other liquid in the system which is contained in the core portion of the unit is congealed and the remaining hot portion of the lubricant or other liquid in the system is flowing in by-passing relationship to said core portion, it acts to raise the temperature of, and thereby to de-congeal, the congealed liquid in said core portion. De-congelation progresses inwardly toward the center of the core portion of the unit and at an accelerated rate as flow through the core portion is resumed, but maximum efficiency of the unit is not restored until all of the liquid in the core portion is de-congealed. Heretofore, however, the construction of units of the type under consideration has been such that complete de-congelation of the liquid in the core portions thereof has required considerable time, whereas it is quite desirable that complete de-congelation be effected as rapidly as possible.

Accordingly, the general object of the present invention is to provide a heat exchange unit of the type under consideration embodying a novel construction whereby the hot portion of the liquid being circulated through the system of which the unit is a part, acts to effect complete de-congelation of congealed liquid in the core portion of the unit far more rapidly than heretofore.

With the foregoing general object in view, the invention consists in a heat exchange unit embodying the novel features of construction, combination and arrangement of parts as will be hereinafter more fully described, illustrated in the accompanying drawings and defined in the appended claims.

50 In the accompanying drawings, wherein like characters of reference denote corresponding parts in the different views—

Fig. 1 is a side elevation of a heat exchange unit constructed in accordance with one practical embodiment of the invention.

Fig. 2 is a fragmentary end elevation of the unit.

Fig. 2a is a fragmentary cross sectional view of the unit on the line 2a—2a of Fig. 1.

Fig. 3 is a horizontal section through the unit on the line 3—3 of Fig. 1; and

Fig. 4 is an enlarged longitudinal section on the line 4—4 of Fig. 2.

Referring to the drawings in detail, 10 designates a casing which contains the heat exchange core portion of the present heat exchange unit, and 11 designates a jacket surrounding said casing and, in conjunction therewith, providing a passageway *a* extending around the outside thereof.

The jacket 11 is provided at a suitable point, at the top and adjacent to one end thereof, for example, with an opening 12 for the inlet of the liquid to be cooled to the passageway *a*, while the casing 10, at a diametrically opposite or substantially diametrically opposite point, at the bottom thereof, for example, is provided with an opening 13 for the inlet of the liquid to said casing from the passageway *a*. In addition, the casing 10 is provided at a point diametrically opposite or substantially diametrically opposite the opening 13, at the top thereof, for example, with an opening 14 for the outlet of the cooled liquid from said casing, and the jacket 11 is provided at a suitable point, at the top thereof, for example, with an opening 15 for the outlet of the liquid from the passageway *a*.

Mounted upon the jacket 11 in covering relationship to the outlet openings 14 and 15 is a housing 16 in the bottom wall of which are openings 17 and 18 which are aligned with the openings 14 and 15, respectively, whereby the liquid may flow into said housing either from the casing 10 or from the passageway *a*. The opening 18 normally is closed, however, by a valve 19 so that the liquid cannot flow from the inlet opening 12 through the passageway *a* and the aligned openings 15 and 18 into the housing 16 in by-passing relationship to the heat exchange core portion of the unit contained in the casing 10, but in its flow to said housing is required to pass through said heat exchange core portion.

As is understood, the present heat exchange unit is to be used in a closed-circuit liquid circulating system such, for example, as the lubricant circulating system of an internal combustion engine employing a pump, or pumps, for circulating the liquid, and in this connection it will further be understood that a delivery conduit from the engine is connected to the inlet opening 12 and that a return conduit to the engine is connected to an outlet 20 in a wall of the housing 16 so that the liquid is returned to the engine regardless of whether it is being circulated through the heat exchange core portion of the heat exchange unit or in by-passing relationship to said heat exchange core portion.

The valve 19 is closed by suitable yieldable means which exerts a closing force thereon not materially greater than the opening force exerted thereon by the normal pressure of the liquid in the system. Thus, while said valve normally is closed and requires the liquid to flow through the core portion of the unit, it may open and permit flow of the liquid in by-passing, non-damaging relationship to the core portion of the unit whenever the pressure of the liquid in the system rises above normal. For example, a sudden acceleration of the speed of the engine may produce a sufficiently high pressure of the liquid

to open said valve, or in the event the liquid in the core portion of the unit should become congealed, the pressure in the system obviously will rise until said valve opens.

In accordance with known practice, the casing 10 has extending therethrough numerous open-ended tubes 21 through which air or any other medium may flow to cool the liquid circulated through said casing between said tubes or, alternatively, any other suitable means may be provided for cooling the liquid during its circulation through said casing. Also in accordance with known practice, spaced apart partitions 22 are provided in the casing 10 for cooperation therewith and with each other to require the liquid to flow in a tortuous path through said casing and to be subjected thoroughly to the cooling effect of the air or other cooling medium flowing through the tubes 21 or their equivalents. In this connection and according to the specific embodiment of the invention illustrated in the drawings, the partitions 22 are disposed horizontally in vertically spaced apart relationship to each other and extend longitudinally of the casing 10 from end to end and from side to side thereof, alternate ones having openings 23 therein adjacent to one end of the casing and the remaining alternate ones having openings 24 therein adjacent to the other end of the casing so that the liquid in flowing from the opening 13 to the opening 14 is required to follow a path extending first in one direction and then in the opposite direction longitudinally of the casing progressively from bottom to top thereof through the successive passes, between the partitions, of the single, continuous passageway formed by said partitions.

A heat exchange unit constructed as set forth in the foregoing is known and is highly efficient in normal operation. When, however, the liquid in the heat exchange core portion of such a unit is cold and congealed and the remaining, hot portion of the liquid in the system is circulated in by-passing relationship to said core portion, considerable time is required for the hot, by-passing liquid to effect de-congelation of the congealed liquid in said core portion, primarily because the de-congelation progresses only inwardly toward the center of the core portion and because there is no initial direct contact of the hot, by-passing liquid with the congealed liquid in the core portion.

Since the unit operates at maximum efficiency only when the core portion thereof is completely free for circulation of the hot liquid therethrough, it is desirable to completely free said core portion of congealed liquid at the earliest moment possible following initiation of flow of hot liquid in by-passing relationship thereto. The present invention is directed to the accomplishment of this purpose and to that end consists in the provision of means whereby hot liquid may find its way from the passageway *a* quickly to the central part of the core portion of the unit and may directly contact the central or core portion of the body of congealed liquid in the core portion of the unit. Thus, the de-congelation process progresses outwardly as well as inwardly and complete de-congelation of the liquid in the core portion of the unit is effected far more rapidly than heretofore.

According to the specific embodiment of the invention illustrated in the present instance, the means for the purpose stated comprises at least one partition 22 which extends across approxi-

mately the middle portion of the casing 10 and which is of double-walled construction with the walls 22' thereof spaced apart to provide a passageway b therebetween. In the casing 10 are openings 25 which afford communication between the passageway a and the passageway b, while in either or both of the partition walls 22' are openings 26 for flow of hot liquid from the passageway b into the casing 10 for direct contact with the liquid on said casing. At least some of the openings 26 are located in the central part of one or the other or both of the partition walls 22' so that hot liquid from the passageway b may contact directly with congealed liquid in the central part of the core portion of the unit. Thus, since the hot liquid which is circulated in by-passing relationship to the core portion of the unit when the liquid in said core portion is congealed, may find its way quickly through the passageway a to the openings 25 and through said openings to the passageway b and thence through the openings 26 into direct contact with the central or core portion of the body of congealed liquid in the casing 10, the de-congelation process progresses outwardly as well as inwardly and complete de-congelation is effected rapidly.

Obviously, even in the absence of any openings 26 in either of the partition walls 22' the hot liquid in the passageway b would effect de-congelation far more rapidly than heretofore. By providing the openings 26, however, and thereby providing for direct contact of the hot liquid with the central part of the body of congealed liquid, de-congelation is effected particularly rapidly.

Although the casing 10 may have openings 25 in only one side thereto to admit hot liquid from the passageway a into only one side of the passageway b, preferably said casing has openings 25 in opposite sides thereof providing communication between opposite side portions of the passageway a and the opposite sides of the passageway b so that the hot liquid may circulate through said passageway b.

Of course, two or more of the partitions 22 may be constructed to operate in the same manner as the single double walled partition described, and in this connection it will be understood that the openings 26 are of small size so that in the normal operation of the system practically all of the hot liquid is required to flow completely through the heat exchange core portion of the unit.

Without further description it is thought that the features and advantages of the invention will be fully understood and appreciated. It is desired to point out, however, that while only a single specific embodiment of the invention has been illustrated and described, the same is readily capable of embodiment in specifically different structures within its spirit and scope as defined in the appended claims.

I claim:

1. A heat exchange unit for use in a closed-circuit viscous liquid circulating system to cool the liquid during its circulation through the system, said unit comprising a casing containing longitudinally disposed coolant conducting tubes and having a jacket providing a passageway extending exteriorly of said casing between substantially diametrically opposite portions thereof, said jacket having an opening for inlet of the liquid to said passageway, said casing having at a point substantially diametrically opposite said inlet opening an opening for flow of the liquid into the same from said passageway and further having at a point substantially diametrically op-

posite said last mentioned opening an opening for flow of the liquid therefrom, said jacket having an outlet opening, a yieldably closed valve normally closing said jacket outlet opening to require the liquid to circulate through said casing and adapted to open under a higher-than-normal pressure in the system to permit the liquid to flow in by-passing relationship to said casing, and partitions in said casing requiring the liquid to follow a tortuous path from end to end of said casing in its flow therethrough, at least one of said partitions comprising spaced apart walls, said casing having a restricted opening for flow of liquid from said passageway into the space between the walls of said partition and at least one of the walls of said partition having openings therein adjacent the center thereof for flow of the liquid from the spaces between said walls into the central portion of the liquid path through said casing, said restricted opening into the space between the walls of said partition being considerably smaller than said space.

2. A heat exchange unit for use in a closed-circuit viscous liquid circulating system to cool the liquid during its circulation through the system, said unit comprising a casing having an inlet and an outlet for the liquid, longitudinally disposed coolant conducting tubes for cooling the liquid during its flow through said casing, means to cause the liquid normally to flow through said casing and to flow in by-passing relationship thereto when the liquid therein is congealed, means defining a passageway exteriorly of and closely adjacent to said casing through which the liquid flows both during its flow to said inlet and during its flow in by-passing relationship to said casing, and partitions in said casing to cause the liquid to flow in a tortuous path from end to end of said casing in its flow therethrough, at least one of said partitions comprising spaced apart walls, said casing having a restricted opening for flow of the liquid from said passageway into the space between said walls and at least one of said partition walls having openings therein in adjacent the center thereof for flow of the liquid from the space between said walls into the casing, said restricted opening into the space between the walls of said partition being considerably smaller than said space.

3. An oil temperature regulator for use in an engine lubrication system and the like wherein the oil is heated in use and circulated under pressure, comprising a plurality of tubes assembled in close parallel relation and open ended for the passage therethrough of a coolant, the oil being caused to flow along and around said tubes whereby to be cooled; a shell enclosing said tube assembly and formed with oil inlet and oil outlet openings, said shell and said tube assembly constituting the core of the regulator; a jacket spaced from and surrounding said core, said jacket defining a conduit for the delivery of oil to said inlet and for a by-passing flow of the oil in the vent of congelation in said core; baffles in said core constraining the oil to follow flow paths parallel to the longitudinal axes of said tubes, at least one of said baffles being of hollow construction and communicating through restricted openings in said shell with said jacket defined conduit at diametrically opposite points thereof whereby to permit a flow of oil in heat exchange relation with the oil in the center portion of the core and in a direction transversely of said flow paths, said restricted openings being considerably smaller than the space within said hollow baffle;

and a plurality of openings in said hollow baffle in the approximate center thereof for injecting oil directly into the flow paths of the core, said injected oil being carried along said flow paths from end to end of the core.
